Inventor:

UNITED STATES PATENT OFFICE.

WILLIAM C. BELL, OF SAVANNAH, NEW YORK.

METAL-ROOFING MACHINE.

SPECIFICATION forming part of Letters Patent No. 231,982, dated September 7, 1880.

Application filed May 1, 1880. (Model.)

To all whom it may concern:

Be it known that I, WILLIAM C. BELL, of 5
Savannah, in the county of Wayne, State of
New York, have invented a certain new and
useful Metal-Roofing Machine; and I do hereby
declare that the following is a clear and
exact description of the same, reference being
given in the accompanying drawings, making
a part of this specification, in which—

10 Figure 1 represents a plan view of the
machine complete. Fig. 2 is a side view of crank
or gear side of the machine. Fig. 3 represents
a longitudinal vertical section of the machine.
Fig. 4 represents a front elevation. Figs. 5
15 and 6 represent details.

Similar letters of reference also represent
like parts in a more minute description.

The object of my invention is to turn up at
right angles the edges of strips of roofing tin
20 or metal suitable and ready for seaming by
being drawn between a succession of rollers
placed relatively to each other, as hereinafter
described.

A represents a roller at the front part of the
25 machine, placed there to support the metal
and to aid in entering the metal strip.

B B represent the guides through which
the strips of tin pass on entering the rollers.
They are formed with grooves to conduct the
30 tin, and are made adjustable by means of slot
and set-screws R R to accommodate the de-
sired width.

C is the lower or under one of the first set
of horizontal rollers between which the tin
35 first enters. This has beveled flanges at either
end.

D is the upper one of the first set, and is
the mate to C. It is beveled off at each end
to match the flange or roller C, into and over
40 which it works, being propelled by cog-gear-
ing O, which is hereinafter described.

E and F are the second pair of rollers, the
lower one, E, having flanges turned nearly at
right angles, and made to revolve by means
45 of the same combination of cog-gearing which
operates the first set above mentioned, above
which, and fitted between said flanges, the up-
per roller, F, is made to revolve by the metal
coming in contact with it.

50 G, the last horizontal roller, is useful for
supporting the metal after it leaves the shap-

ing-rollers, also for holding it in position to be
operated upon by the short upright rollers H H
at each end, which are made adjustable at M.
These upright rollers H H are set with the 55
tops inclining toward the center of the ma-
chine, and as the strip passes over the roller G
they force the turned edge to an angle smaller
than the one required, which is necessary to
offset the spring of the metal, and thus leave 60
the edge at a right angle to the body of the
metal strip.

The upper roller of each set is held above
the lower ones in boxes P, formed in an up-
right adjustable section, in either edge of 65
which are grooves. Upright openings are
formed in the sides of the machine to receive
these sections, into the grooves of which the
side plates of the machine are fitted, holding
them firmly in their place. The lower roller 70
of each set is held in a similar manner, but in
a separate grooved section or box, which, by
being detached, (the upper from the lower
rollers,) allows the latter to rise or fall inde-
pendently of the former.

The sections holding the upper rollers are
held down and firmly pressed upon the lower
by means of caps J and set-screws L, under
which are rubber springs K, to admit of a
greater separation of the rollers for the pas- 80
sage of locked seams or any other unusual
thickness.

The shafts of the rollers pass through the
boxes on one side of the machine and connect
on the outside with a combination of cog- 85
gearing, O, and a wheel-crank, N, from which
both sets of rollers receive simultaneous
motion.

When in use the machine is placed upon the
90 roof and the tin is run through it from a roll
or strip, usually made the length of the roof.
The tin passes through the guides B B and is
drawn between the rollers C and D. The
bevel-roller D, matching into the flanged roller
95 C, partially turns up the edge. It is then
caught by rollers E and F and turned up nearly
to a right angle. It then passes over roller G,
when the upright rollers H H force it inward
beyond a square turn; but as it leaves the ma- 100
chine the spring or elasticity of the metal leaves
it at a perfect right angle.

The advantages of my invention are: It does

the work smoothly and does not check or crack the soldered seams as the case is when the edges are turned to a right angle by the usual process. It does the work rapidly and uniformly, which has hitherto been done by a more expensive, slow, and less perfect method.

Having thus described my invention, what I claim as new, and desire to secure by Letters Patent, is—

- 10 The combination of guides and of horizontal rollers, with flanged and beveled ends to

match, with the upright adjustable rollers H H, for simultaneously turning both edges of metallic roofing-strips to any required angle by a continuous movement of the metal strip through and between said rollers, and with means for operating the horizontal rollers.

WILLIAM C. BELL.
